KNITTING OF GARMENTS ON STRAIGHT-BAR MACHINES AND IN MEANS THEREFOR

Harry Wilfred Start, Carlton, and Ernest Start, Wilford, England, assignors to George Blackburn and Sons Limited, Nottingham, England

Application December 17, 1936, Serial No. 116,400
In Great Britain November 29, 1935

6 Claims. (Cl. 66—60)

This invention relates to improvements in the method of knitting garments on straight-bar machines and in means therefor, and it is specially adapted to the knitting of hose in which the leg and fore part of the foot are knitted without any interruption or break, and the parts which form the heel are subsequently knitted on the same or a different machine.

In order to knit the heel parts after finishing the fore part of the foot, a start of a new course has to be made at an intermediate point in the foot portion already knitted, and this can at the present time only be done on a machine which is specially constructed for the purpose.

15 In order to overcome this difficulty, a special appliance is provided which is adapted to knit a first course at an intermediate point in a garment, and will facilitate the subsequent transfer of this course to an ordinary knitting machine where the 20 knitting of the heel parts can be completed. The reason the first course cannot be knitted at an intermediate point in a garment on an ordinary machine, is, that part of the already knitted garment must in this case be disposed on the inner 25 side of the needles, and the knocking over bits which are disposed just below the sinkers in a machine of the "cotton" type on which such hose are knitted, will not permit of this course being adopted.

30 According to this invention, the special appliance comprises a needle bar with tricks in which a series of butted needles are disposed, a cam box which engages with the needle butts and can be traversed by hand, a presser bar which can be 35 moved away from the needles, a series of bits on which the courses are drawn and knitted and which bits can be raised and lowered by means of a hand lever, and a detachable bar with transfer points disposed so that the loops can be readily 40 transferred from the needles on to the said points.

The invention will now be described with reference to the accompanying drawing, in which

Fig. 1 is a front elevation, and

45 Fig. 2 an end elevation of appliance for knitting courses at intermediate points in a garment or piece of fabric constructed according to this invention.

Fig. 3 is a vertical cross section of the appliance.

50 Fig. 4 is a view showing the knitting cams detached.

Figs. 5 to 9 inclusive are diagrams illustrating the operations performed on the appliance.

Like letters indicate like parts throughout the 55 drawing.

In the preferred construction which is shown in the drawing, a series of preferably bearded needles A are disposed vertically in tricks in a needle bar B, which latter is as shown, secured to a rail C which carries the whole of the mechanism. The rail C may be mounted on standards or secured at a convenient height to a fixture.

The needles A are independent, that is, they can slide in the tricks in the needle bar B, so that they can be operated in succession and will thus draw their own loops in the yarn supplied to them, and the use of sinkers is not necessitated. In order to operate these needles in succession, they are formed with butts A¹ which engage in knitting cams in a cam box D which is disposed at the front of the needle bar B and is adapted to slide on two shafts E disposed in front of and parallel to the needle bar B. The ends of these two shafts E are secured in end brackets F secured to the rail C, and the cam box D thereon is fitted with ordinary knitting cams D¹ which are adapted to draw the needles down when it is traversed from right to left as seen in Fig. 1, and are adapted to raise the needles again when it is traversed from left to right.

Associated with the knitting cams D¹ which are shown more clearly in Fig. 4, is an extension J of the cams in the cam box D, and this extension J is located under the butts A¹ of the needles A and holds them all up when the cam box is on the right as shown in Fig. 1. This facilitates the operation of running the work on the needles as the latter cannot then be pushed down. Attached to the cam box D is a handle D² by means of which the cam box can be conveniently traversed, and associated with this handle is an arrangement for performing another operation that will be hereinafter described.

A presser bar K is provided, and it is carried on the upper free ends of side arms L which are mounted on a shaft M carried in bearings M¹ in the brackets F, so that the said bar K can be moved back out of the way when work is being run on the needles, springs L¹ connected to the arms L being provided to hold it in its operative position in which it is shown in Fig. 2.

The presser bar K is drawn back as described by the following arrangement. The arms L are formed with forward extensions L², and a bar G which is secured to these extensions is disposed just below the cam box D. This bar is provided with raised parts G¹ at each end, and a roller G² on the cam box D which runs along the bar, acts upon the raised parts G¹ and depresses the bar G at the end of each traversing movement

and thus withdraws the presser K from the needles.

Above the needles A is a longitudinal bar V¹ fitted with transfer points V. This bar V¹ is not fixed, but its ends are carried in recesses disposed at the upper ends of brackets W secured to the rail C. This bar V¹ is not in position when the courses are drawn, but is placed in position after this operation in order to receive the loops, and 10 is then removed with the work.

The cam box D for actuating the needles A, is further fitted in addition to the knitting cams, with a thread carrier D³ to which a supply of yarn is carried, and associated with this thread carrier is a spring clip D⁴ to hold the loose end of the yarn.

In the present arrangement, the courses are drawn and knitted on the bits P which project between the needles and are carried on a bar P¹. 20 These bits P are similar to the knocking over bits in an ordinary machine, but perform a different office, that is, the courses are drawn and knitted directly upon them, and they are raised in order to transfer the loops from the needles A 25 to the transfer points as will be hereinafter described. This arrangement obviates the necessity for actuating the needles A and the points V when transferring the loops from the former to the latter, and simplifies the construction of the 30 appliance and its operation.

In order to raise the bits P, the bar P¹ is carried on the upper end of arms Q which are secured on a shaft Q¹, the shaft Q¹ is mounted in the upper ends of side links R which are mounted on 35 a shaft S which is mounted in short arms S¹ secured on a shaft T fitted with a hand lever T¹. The shaft T is mounted in bearing T² in the end brackets F and by depressing this hand lever T¹ on the shaft T, the bits P can be raised high 40 enough to transfer the loops from the needles A, to the transfer points V which are carried on the detachable bar V¹.

The bits P are further moved in between the needles to a more or less extent as required by 45 the following arrangement. The handle D² associated with the cam box D is mounted on a member D⁸ which is pivoted at D⁵ to the said box, and the member D⁸ is thus turned about its pivot each time it is used to traverse the cam box. 50 Disposed on the member D⁸ are two cam parts D⁶ and D⁷, and these cam parts act on the shaft Q¹ and draw the bits P back a little when drawing a course and let them in so that the hooks thereon will hold the work down when the needles are 55 being raised. The shaft Q is held up to the cam parts D⁶ and D⁷ by means of a spring Q² connected to its end.

In front of the needles is a shield Y in which the front part of the work can be placed when 60 drawing the course and this shield is secured to the bar P¹ which carries the bits P.

In the case of a hose for example which is completed all but the heel parts, the knitted course at the point where the heel pieces are to start, 65 is run on the needles A of the appliance described as shown in Fig. 5, with, as is necessary, part of the hose X in front and part at the rear of the needles, where there is no obstruction. The cam box D is then traversed to the left so as to knit 70 a course, and while the needles A are down (see Fig. 6), the part of the garments X at the front of the needles is then turned to the rear as shown in Fig. 7, that is, to the same side as the other part, and the needles A are then raised by 75 traversing the cam box D to the right, leaving

the new course on the needle stems as shown in Fig. 8.

The loops of the course now on the needles or those of any succeeding course that may be knitted, can now be transferred to the transfer points V on the bar V¹ which is placed in position in the brackets W, by raising the bits P, and when this operation is completed, the bar V¹ which carries the transfer points V can be removed together with the garment, as shown in Fig. 9. The loops on the points can then be subsequently readily transferred to the needles of an ordinary knitting machine, where the remainder of the heel parts can be knitted.

The advantage of the arrangement described, 15 is, that it does not necessitate the provision of special facilities for performing this operation on each of the ordinary machines employed in knitting hose, and as the operation of running on and knitting the first courses and transferring the 20 loops to points on transfer bars, ready to transfer them to a machine, is done on the independent appliance, the ordinary machines are not kept standing while the operation is being performed in each separate division of the same, 25 and consequently a considerable saving in time is effected.

A further advantage is that the same appliance can be adapted for performing the same operation when required, on any kind of knitted garment or article.

What we claim is:—

1. Apparatus for knitting a course at an intermediate point in a garment, comprising in combination, a needle bar with butted needles mounted in tricks therein, a hand traversed needle actuating cam box with cams to engage with the needle butts, a thread carrier on the cam box, bits associated with the needles on which the courses are drawn and knitted, a presser bar which 35 can be moved away from the needles so as to leave the latter clear for running on and a detachable bar with points disposed so that the loops of the courses knitted on the needles can be readily transferred thereto, substantially as 40 described.

2. Apparatus for knitting a course at an intermediate point in a garment comprising in combination, a needle bar with butted needles mounted in tricks therein, a hand traversed needle actuating cam box with knitting cams which 50 are extended to one side of the cam box so as to hold up the needles when the cam box is at one end of the needle-bar, a thread carrier, bits associated with the needles on which the 55 courses are drawn and knitted, a presser bar movable away from the needles, and a detachable bar with points disposed so that the loops of the courses knitted on the needles can be readily transferred thereto, substantially as described.

3. Apparatus for knitting a course at an intermediate point in a garment comprising in combination, a needle bar with butted needles mounted in tricks therein, a hand traversed needle actuated cam box with cams to engage with the 65 needle butts, a thread carrier, bits associated with the needles on which the courses are drawn and knitted, a presser bar movable away from the needles, a detachable bar with points disposed so as to engage with the needles and 70 means for raising the bits associated with the needles in order to transfer the loops from the needles to the points, substantially as described.

4. Apparatus for knitting a course at an intermediate point in a garment comprising in 75

combination, a needle-bar with butted needles mounted in tricks therein, a hand traversed needle actuating cam box with cams to engage with the needle butts, a thread carrier, bits associated with the needles on which the courses are drawn and knitted, a presser bar movable away from the needles, a detachable bar with points disposed so that the loops of the courses knitted on the needles can be readily transferred thereto, a pivoted handle on the cam box, and cams associated therewith adapted to move the bits associated with the needles into engagement with the latter to a more or less extent, substantially as described.

15 5. Apparatus for knitting a course at an intermediate point in a garment comprising in combination, a needle bar with butted needles mounted in tricks therein, a hand traversed needle actuating cam box with cams to engage with the needle butts, a thread carrier, bits associated with the needles on which the courses are drawn and knitted, a presser bar carried by arms on a shaft, a bar provided with cam lifts at each end secured to said arms and disposed along the underside 15 of the cam box, a roller on the cam box bearing on the said bar so that the presser is withdrawn from the needles by the cam box at each end of its traverse, and a detachable bar with points disposed so that the loops of the courses knitted 20 on the needles can be readily transferred thereto, substantially as described.

20 25 diles can be transferred thereto said bar being

detachably mounted in recesses in brackets disposed so that it can be removed with the loops of a knitted course together with the garment in which the course is knitted substantially as described.

5

6. Apparatus for knitting a course at an intermediate point in a garment comprising in combination, a needle bar with butted needles mounted in tricks therein, a hand traversed needle actuating cam box with cams to engage with the needle butts, a thread carrier, bits associated with the needles on which the courses are drawn and knitted, a presser bar carried by arms on a shaft, a bar provided with cam lifts at each end secured to said arms and disposed along the underside 15 of the cam box, a roller on the cam box bearing on the said bar so that the presser is withdrawn from the needles by the cam box at each end of its traverse, and a detachable bar with points disposed so that the loops of the courses knitted 20 on the needles can be readily transferred thereto, substantially as described.
